ASH REMOVING GRATE FOR OVENS

Filed April 6, 1929

INVENTOR.
Michael Landeck
BY *Gordon D. Holachek*
ATTORNEY

UNITED STATES PATENT OFFICE

MICHAEL LANDECK, OF BROOKLYN, NEW YORK

ASH-REMOVING GRATE FOR OVENS

Application filed April 6, 1929. Serial No. 353,026.

This invention relates to new and useful improvements in ash removing grates for ovens.

The invention has for an object the provision of a device of the class mentioned which is of simple durable construction, dependable in use and efficient in action, and which can be manufactured and sold at a reasonable cost.

- 10 The invention proposes the use of an outer stationary frame with its front frame arm having its inner face formed with a flat rearward inclined top portion and a bottom forward inclined portion, its rear frame arm 15 having its inner face formed with a top flat rearward inclined portion and a bottom forward inclined portion, an intermediate grate frame to be pivotally supported by the outer frame and arranged for normally maintaining a horizontal position, and the intermediate grate frame to support an inner grate frame slidably mounted and arranged to raise at its extremities of its sliding amplitude for shuffling a fire bed on the grate.
- 20 For further comprehension of the invention, and of the objects and advantages thereof, reference will be had to the following description and accompanying drawings, and to the appended claims in which the various 25 novel features of the invention are more particularly set forth.

In the accompanying drawing forming a material part of this disclosure:—

Fig. 1 is a plan view of a grate constructed according to this invention.

Fig. 2 is a side elevational view looking in the direction of the arrows 2—2 of Fig. 1.

Fig. 3 is an enlarged fragmentary sectional view taken on the line 3—3 of Fig. 1.

Fig. 4 is a fragmentary enlarged sectional view taken on the line 4—4 of Fig. 1.

Fig. 5 is a fragmentary enlarged sectional view taken on the line 5—5 of Fig. 1.

Fig. 6 is a view similar to Fig. 5 but illustrating a modification.

The reference numeral 10 indicates generally an outer stationary frame consisting of a front frame arm 11, a rear frame arm 12 and side arms 13. The front frame arm 11 has its inner face formed with a flat rear-

ward inclined top portion 14 joining with a bottom forward inclined portion 15. The rear arm 12 has a top flat rearward inclined portion 16 joining with a bottom rearward inclined portion 17. An intermediate grate 18 is provided with trunnions 19 engaging in recesses 20 formed in the side arms 13 of the frame and communicating with the top face.

The intermediate grate 18 consists of a front frame arm 21, a rear frame arm 22 and side arms 23. The front frame arm 21 has its outer face formed with a top rearward inclined portion 24 normally engaging against the portion 14 of the outer frame for holding the intermediate frame against pivoting in one direction. The rear frame arm 22 of the intermediate frame has its outer face formed with a rearward inclined top portion 24' normally engaged against the rearward inclined portion 16 of the outer frame for holding the intermediate frame against rotation in the same direction as before referred to. The lower portions of the outer faces of the front and rear frame arms are inclined to permit rotation of the intermediate frame in a direction opposite to the one before referred to.

The intermediate frame has a plurality of longitudinal grate bars 25 arranged so that one of these bars coincides with the center of the frame. This central bar has a bottom extension 26 formed with an aperture 27 for engagement by an oven poker for rotating the intermediate frame to drop a fire bed off the grate.

An inner grate frame 28 has a plurality of grate bars 29 arranged so that a pair of these bars straddle the center one of the bars 25. The pair of bars just referred to have bottom extensions 30 formed with apertures 31 for receiving a poker so that the inner grate frame may be reciprocated back and forth. Each of the longitudinal grate bars 25 are formed with top recesses 32 at their front and rear ends. Each of these recesses have a top portion indicated by numeral 33 and formed with front and rear inclined ends, an intermediate portion 34 and a base portion 35. The front and rear frame arms of the inner frame are formed with a plu-

rality of bottom recess portions 36 engaging the portions of the arms 25 directly beneath the recesses 32.

The front and rear faces 37 of the front 5 and rear frame arms of the inner frame are inclined as clearly shown in Fig. 5 so that when the inner frame is reciprocated back and forth, these inclined sides engage against the inclined ends of the recess portions 33 for 10 camming the inner frame upwards. Pins 38 project from the front and rear frame arms of the inner frame and extend into the base recess portions 35 and have bottom heads 39 preventing complete disengagement of the 15 inner frame when cammed up in a raised position.

In the modified form of the device illustrated in Fig. 6, a plate 40 has been secured on the bottom of a longitudinal grate bar 25 20 and has upward projections 41 extending thru apertures in the grate bar so as to extend into the base portions 35 of the recess providing hills engageable by a roller 42 on the bottom of the pin 38'. As the inner grate 25 is reciprocated back and forth the roller 42 rides up and down on the hill portion 41 for shuffling a fire bed upon the grate.

In operation of the device a poker may be engaged in the apertures 31 and the inner 30 grate frame reciprocated back and forth for shuffling a fire bed thereon. At the end of each stroke of the inner grate frame it is caused to rise due to the inclined sides 37 as above referred to. The pins 38 prevent 35 complete engagement during rising. When it is desired to throw the bed of fire from the grate the poker may be engaged in the aperture 27 and the intermediate grate frame rotated about the trunnions 19.

40 While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

50 1. In an ash removing grate for ovens, a stationary frame, an intermediate frame having grate bars and pivotally mounted on said stationary frame, and an inner frame with grate bars slidably mounted on the intermediate frame, and limited in its amplitude of motion, and arranged to rise at the beginning and end of each stroke for shuffling a fire bed on the grate, said inner frame being within said intermediate frame so that the 55 latter frame accomplishes the said limiting of motion of the inner frame, and the intermediate frame being formed with inclined surfaces engageable by inclined surfaces on the inner frame to accomplish the said raising at the beginning and end of each stroke.

2. In an ash removing grate for ovens, a stationary frame, an intermediate frame having grate bars and pivotally mounted on said stationary frame, and an inner frame with grate bars slidably mounted on the intermediate frame, and limited in its amplitude of motion, and arranged to rise a number of times during each stroke, said raising being accomplished by a plate attached on said intermediate grate and formed, with projections forming hills, and a roller supported on the inner grate and engaging the hills, said inner frame being within said intermediate frame so that the latter frame accomplishes the said limiting of motion of the inner frame.

In testimony whereof I have affixed my signature.

MICHAEL LANDECK.
